STORAGE RESERVOIR FOR LIQUEFIED
GASESHowell C. Cooper, Sewickley, Pa., assignor to
Pittsburgh-Des Moines Company, a corpora-
tion of Pennsylvania

Application January 8, 1945, Serial No. 571,804

9 Claims. (Cl. 220—15)

This invention relates to reservoirs for storing liquefied natural gas for consumption as gas when desired.

It is well known that natural gas is now carried through pipe lines as gas from wells to points of consumption, and that much of it is thus carried several hundred miles through lines that are expensive to lay as well as to maintain. In an increasing number of localities the demands for gas, in some places the normal and in some places the peak demands, are such that the existing lines and gas pumping facilities are inadequate to supply sufficient gas. Although it has been proposed to meet this condition by liquefying natural gas at or near gas wells and transporting it to points of consumption as a liquid, and also by liquefying at or near points of consumption the gas that is not required at low demand periods and later returning it to the lines as gas during high demand periods, I have no knowledge of any facilities, prior to my invention, that are capable of storing liquefied natural gas in the manner necessary to meet the safety, efficiency and other requirements incident to thus supplying or supplementing the supply of natural gas.

The general object of this invention is to provide a reservoir of large capacity for liquefied natural gas in which it may be stored safely and with little loss due to evaporation or gasification, and a special object is to provide a stationary reservoir of the type stated which is particularly suitable for storing liquefied natural gas at or near its place of consumption.

The invention is illustrated in the accompanying drawings in which Fig. 1 is a side view in elevation of a reservoir of this invention for storing liquefied natural gas.

Fig. 2 is a top plan view of the reservoir of Fig. 1;

Fig. 3 is an enlarged fragmentary view partially in elevation and partially in section, the section being taken through the center of the container adjacent the inlet and outlet structure shown in Fig. 1;

Fig. 4 is a detail view of the outer end portion of the inlet and outlet structure shown in elevation in Fig. 1 and in section in Fig. 3, looking at the same from below;

Fig. 5 is a fragmentary vertical central sectional view taken at the top of the reservoir and includes the waste gas outlet conduit; and

Fig. 6 is a fragmentary vertical sectional view through a mid portion of the reservoir showing the attachment of one of the supporting columns

thereof and the insulation between the inner tank and the outer casing adjacent such mid portion.

There are several known procedures for liquefying natural gas whose liquefaction temperature is about -250° F. at atmospheric pressure, one of such procedures being that used for recovering helium from natural gas containing it. Any of such procedures may be used for liquefying natural gas for storage in the reservoir provided according to my invention. Such reservoir includes an inner tank and an outer casing whose walls are spaced from each other throughout. The space between those walls is filled with a body of insulation which forms the sole support 10 for the inner tank by the outer casing, thus avoiding the use of such metal structural supports as would readily conduct heat to the tank. The outer casing is supported exteriorly, as by 15 columns, in such a way that the reservoir and its apurtenances are positioned above or out of 20 contact with heat conductors. When a very large capacity is desired, the reservoir is preferably spherical in form, the inner tank being substantially concentric with the outer casing.

Liquefied natural gas is introduced into and withdrawn from the reservoir by a conduit extending through the bottom of, and which preferably extends laterally beneath, the reservoir. Regardless of the effectiveness of the insulation 30 of the tank, there is normally some evaporation or gasification of the liquefied natural gas due to some infiltration of heat, in view of which provision is made for the escape of such gas by causing it to flow through a conduit having an inlet near the top of the tank and extending downwardly through the bottom of the reservoir. Preferably this waste gas conduit surrounds the liquid conduit so that the low temperature waste 35 gas in effect insulates the liquefied gas conduit. For further insulating the latter, a shell surrounds and is spaced from it, the shell preferably being attached to the bottom of the casing, and the space between it and the waste gas conduit being filled with insulation.

Other features of the invention will be explained with reference to the reservoir shown in the accompanying drawings which includes an inner tank 1 and an outer casing 2, each of which is preferably formed of shaped plates of 40 steel whose edges are welded to form a securely sealed structure. Because of the very low-temperature working conditions of the inner tank, it may be formed of a low carbon nickel steel containing about .08 per cent carbon and about 3.5 per cent nickel. Other metals such as copper,

aluminum and alloys of various kinds, which retain sufficient ductility at low temperatures, may also be used for forming the tank.

In the space between the tank and casing below the mid section of the reservoir there is insulating means which has sufficient strength to itself support the tank substantially concentric within the casing when the tank is filled with liquefied natural gas, and which insulating means has a relatively low thermal coefficient of expansion so that it will not prejudicially contract when cooled by the liquefied natural gas.

This insulating means provides a member in the form of a segment of a hollow sphere which not only serves as a cradle for supporting the tank during its construction, but as a foundation for supporting the tank and its contents of liquefied gas by the casing.

It has been found that this cradle in the form of a hollow spherical segment of insulation can be built up from blocks or slabs of foam glass, blocks of balsa or other wood having a low thermal conductivity, or of cork board.

If foam glass is used, it can be sawed into blocks or slabs which, when laid up in staggered joint fashion, will substantially conform to the curvature of the casing shell. If wood blocks are used, they are also preferably arranged in layers with the joints staggered. They are so arranged that the grain of the wood extends substantially perpendicular to the inner surface of the casing shell, since wood is of lower thermal conductivity lengthwise of the grain than across the grain. When cork board is used, it is also laid in layers in staggered joint fashion.

It has been found that among the materials now available cork board is the most satisfactory. Wood, such as balsa wood, is the next most satisfactory and foam glass is least satisfactory of these three materials from the standpoint of thermal conductivity.

All three of these materials, however, are characterized by their ability to withstand temperatures below -100° F. without progressive compacting during low temperature use of the reservoir and without material increase in capacity to conduct heat.

Cork board has a lower thermal conductivity than balsa or any other wood with which I am familiar, and balsa wood has a lower thermal conductivity than foam glass. These three materials, however, have sufficient strength for use in forming the cradle for supporting and holding the inner tank shell substantially concentric with the outer casing.

Instead of extending the cradle up to the mid section of the container, it will function satisfactorily if it only extends up 45° from the center of the lower polar region of the casing, since this will be sufficient to support the load made up of the tank and its contents and hold the tank concentric with the casing.

In constructing the reservoir, the outer casing is first welded upon suitable forms up to about the mid section of the reservoir, and thereafter the layers of insulating material in the form of slabs or blocks are progressively laid with the joints between the blocks or slabs in one layer staggered with relation to those in the adjacent layers. These layers are laid upon the inner wall of the casing beginning from the bottom center and working upwardly in all directions. When the entire thickness of the cradle is thus formed, the metal plates forming the inner tank are laid upon the cradle and the plates are welded to-

gether in place, the cradle being thus firmly held in place between the outer and inner walls of the reservoir.

Above the cradle the inner tank wall is built up before building the outer casing. Thereafter the space between the tank and casing above the cradle is filled with granular or loose fibre forms of insulation 4, preferably granulated cork, which is compacted between the walls.

The entire reservoir shown in the drawings is supported solely by a plurality of columns which hold it otherwise out of contact with any heat conducting surface or structure. As shown in Fig. 6, columns 5, which may be in the form of H-sections, are welded to the mid section of the outer casing, the flanges of each H-section being cut to conform with the curvature of the casing and being welded to it through suitably curved angles 6. At the mid section of the reservoir a working platform 7, extending entirely around the reservoir, is conveniently attached to columns 5. Also, for strengthening the upper portion of the outer casing it is provided with ribs 8, as shown in Figs. 1 and 2, and for stabilizing the columns their tops and bottoms are cross connected to each other by tie rods 9.

For the discharge of waste gas, which is normally formed in the tank due to an unavoidable small infiltration of heat, a waste gas conduit 10 extends from near the top of the tank downwardly through the bottom of the reservoir. At its top, tank 1 is provided with an opening which receives a hood 11 that surrounds the top of conduit 10 and has its outer face welded to the wall of the opening formed in tank 1. As shown in Fig. 5, the upper end of conduit 10 is slidably positioned in hood 11 to permit movements of the end of the conduit within the hood due to thermal expansion and contraction of the conduit. This hood is provided with a plurality of openings 12 for the passage of waste gas from the tank into the top of conduit 10 in the manner generally indicated by the arrows in the hood. The lower end of conduit 10 extends through the bottom of the reservoir and projects laterally beneath it, as shown in Figs. 1 and 3, it being provided with expansion joints 13 which, as indicated, may be of the Sylphon tube type. The outer end of conduit 10 is provided with a fitting 15 for attachment to a conduit 14 leading to a pipe line from which the gas can be used, or the gas can be reliquefied.

As an emergency measure, provision is made for venting waste gas from conduit 10 in the event of such rapid generation of gas in the tank that a material increase in internal tank pressure ensues. For this purpose a conduit 16 may be attached to the outer end of conduit 10 and extend upwardly to the upper portion of the reservoir where waste gas may be safely vented to the atmosphere through a suitable weighted or otherwise controlled check valve 17.

A conduit 20 for conducting liquefied natural gas to and discharging it from tank 1 extends concentrically through waste gas conduit 10 and is adapted at its outer end to be connected to a conduit 19 disposed in conduit 14 and leading from suitable liquefaction apparatus. At its inner end, beneath the reservoir, conduit 20 preferably projects through the elbow of conduit 10 and upwardly to a position a short distance above the bottom of the tank. Surrounding the portion of waste gas conduit 10 immediately above the bottom of tank 1 there is a perforated drum 21 within which liquefied gas is discharged from

an orifice 22 at the upper end of conduit 20, and from which it flows into tank 1. For controlling flow through conduit 20 its orifice 22 is provided with a valve 23 which is adapted to be raised and lowered, as desired, by a cable 24 whose upper end is attached to a rod that extends upwardly through suitably packed joints in the tops of the tank and casing walls.

Surrounding conduit 10, and spaced from it a substantial distance, there is a shell 30 which, as shown in Fig. 3, has an inner open end welded at 31 to casing 2 whose bottom is provided with an opening to receive conduits 10 and 20. The space between conduit 10 and shell 30 is filled with insulation to insulate liquid gas conduits 10 and 20.

To prevent the accumulation of gas pressure in the event of leakage of gas through the wall of tank 1 or its pipe connections 10-20, the top of casing 2 is provided with suitable relief valves 35 which are connected to an inverted cup-shaped structure 36 whose outer face is welded to the wall of an opening formed in casing 2 to receive it. Thus if gas pressure builds up in the insulation between tank 1 and casing 2, pressure will be relieved before any damage to tanks 1 and 2 occurs.

Further features of the reservoir here provided will now be explained with reference to the preparation of the reservoir for use, and the description of its operation. After the reservoir has been fully constructed and insulated, the insulation is preferably dried and its voids supplied with a gas having low liquefaction and freezing points so that it will remain in its gaseous form, and which is inert to preclude combustion in the event of accidental accumulation of gas in the insulation space. For this purpose dry air or other gas may be forced through the insulation by a pump 40, diagrammatically shown in Fig. 1, having a conduit 41 connected to its inlet and a conduit 42 extending from its outlet to one side of a dehydrator 43, from the other side of which a conduit 44 extends to the outer end of shell 30. Conduit 44 may contain a heater 39 for heating the air supplied by pump 40 to the insulation between waste gas conduit 10 and shell 30. The heated air then passes from the shell upwardly through the body of insulation between the walls of tank 1 and casing 2 to remove moisture from the insulation and to expel moist air and other gases and vapors from it, such air and gases escaping through manholes 45, which are then open, in the top of casing 2. Thereafter an inert gas having low liquefaction and freezing points, such as nitrogen or products of combustion, may be similarly pumped into and through the insulation so that its voids will be sufficiently free from oxygen that combustion will not take place in the insulation in the event of leakage of gas through the wall of tank 1. If desired, the drying of the insulation may be effected by the inert gas instead of first pumping heated air into and through the insulation. To maintain a predetermined static pressure within the insulation space, pump 40 may later be used to supply additional gas to that space to compensate for changes in the volume of the space due to thermal contraction of the tank and of the insulation when the tank is supplied with liquefied natural gas.

When the insulation is dried and supplied with inert gas, the reservoir is in condition to be filled with liquefied natural gas which flows into it through conduit 20 from the last stage of a

liquefaction apparatus in which the liquefied gas may be at a temperature of about -160° F. and under a pressure of 600 pounds. The reduction of the high pressure on the liquid to atmospheric pressure results in vaporization or gasification of a portion of the liquid and a reduction of the temperature of the remaining liquid to about -260° F. at which it remains liquid under substantially atmospheric pressure. The gas thus formed flows through waste gas conduit 10, and at its low temperature is led to the compressor of the liquefaction apparatus in which it is again liquefied.

During the filling of the tank with liquefied gas, valve 23 is raised from orifice 22 at the top of conduit 20 and is returned to its seat to close the orifice when liquefied gas is not flowing into the tank. The mixture of liquid and gas then remaining in conduit 20 may be withdrawn as a safety precaution to prevent the building up of pressure within that conduit. When it is desired to remove liquefied natural gas from tank 1 for supplying it as gas to a line, valve 23 is raised. Near the end of conduit 20 a conduit 50 is attached to it for the discharge of liquefied gas, conduit 50 extending within the gas relief conduit 16 and through its side. The liquid then flows to a heater for converting it into gas which is discharged into a supply line.

In thus storing liquefied natural gas it is highly desirable that there be a minimum infiltration of heat in the tank. To this end an important feature of the invention resides in supporting the tank solely by the body of insulation 35 between it and the casing surrounding it, and in turn supporting the casing solely by columns or other means so that the reservoir and the filling and discharge instrumentalities connected to its bottom be free from contact with anything that would afford a path for relatively rapid conduction of heat. Further important features reside in the construction and arrangement of the liquid and gas filling and discharge instrumentalities, and in the character of the insulation.

By way of example, but without limitation of my invention, a reservoir the same as herein shown and described, and constructed for the purpose herein explained, has been built. The diameter of the inner tank is approximately 57 feet and that of the outer casing is approximately 65 feet, with a space of about 4 feet in thickness between them filled with insulation. The tank has a liquefied gas capacity sufficient to form approximately fifty million cubic feet of gas at a temperature of 60° F. under a pressure of 30 inches of mercury. Thus in one reservoir there may be stored more than five times as much gas as can be held in a modern ten million cubic foot gas holder, the cost of constructing which materially exceeds that of this reservoir. In this reservoir the waste gas conduit 10 is eighteen inches in diameter, which is sufficiently large to remove gas from the tank as rapidly as the gas could be formed in the inner tank if that tank were uninsulated.

The weight of the tank shell is approximately 160,208 pounds and the weight of the liquefied gas stored in such tank is approximately 2,160,000 pounds; the total load supported by the insulating cradle is, therefore, approximately 2,320,208 pounds, and since the temperature of the liquefied natural gas and therefore of the tank shell is in the neighborhood of about -250° F. at atmospheric pressure, it will be appreciated that

this insulating cradle is an important feature of this invention.

According to the provisions of the patent statutes I have explained the principle and operation of my invention and have illustrated and described a typical commercial embodiment of it. However, I desire to have it understood that, within the scope of the appended claims, the invention may be practiced otherwise than herein illustrated and described.

This is a continuation in part of my copending application Serial No. 367,403 filed by me on November 27, 1940, now abandoned.

I claim:

1. A reservoir for storing liquefied natural gas for discharge as gas into a supply line, said reservoir comprising an inner spherical tank and an outer spherical casing whose wall is substantially concentric with that of the tank, means for supporting said casing from its exterior, and a body of insulation consisting of cork board in the lower and granular cork in the upper portion of the space between the walls of said tank and casing, the cork board forming the sole support of the tank by the casing.

2. A reservoir for storing a relatively great quantity of liquefied gas, comprising an inner substantially spherical tank, an outer substantially spherical casing concentrically arranged with relation to such tank and spaced a substantial distance therefrom, means for supporting such casing above the ground and a cradle for supporting the tank from the casing, having the form of a circular section of a hollow sphere the center of the surface of which coincides with the center of the lower polar region of the casing, and extends upwardly therein at least 45° from such center; such cradle being formed from pieces of slab-like material of low thermal conductivity arranged in a number of superimposed layers with the joints between the pieces forming one such layer staggered with relation to those between the pieces forming the adjacent layers; such material being characterized by its ability to withstand temperatures below -100° F. without progressive compacting and without any material increase in its capacity to conduct heat when subjected to the weight of the tank and its contents of liquefied gas.

3. A reservoir as defined in claim 2, in which the slab-like material from which the cradle is formed is corkboard.

4. A reservoir as defined in claim 2, in which the slab-like material from which the cradle is formed is balsa wood having its grain extending substantially perpendicular to the inner surface of the casing.

5. A reservoir as defined in claim 2, in which the slab-like material from which the cradle is formed is foam glass.

6. A reservoir for storing a relatively great quantity of liquefied gas, comprising an inner substantially spherical metal tank, an outer substantially spherical metal casing concentrically arranged with relation to such tank and spaced a substantial distance therefrom, means for supporting such casing above the ground, means located within the bottom portion of the casing, having the form of a circular section of a hollow sphere and forming a cradle upon which the tank is constructed and which constitutes the sole means for supporting within the casing the tank and its contents of liquefied gas, and finely divided insulating material substantially filling the space between such tank and casing above such cradle; such cradle being formed of sections of slab-like material of low thermal conductivity arranged in a number of superimposed layers with the joints between sections in each layer staggered with relation to those in the adjacent layers; such cradle being characterized by its ability to withstand temperatures below -100° F. without progressive compacting and without any material increase in its capacity to conduct heat during use of the reservoir.

7. A reservoir as defined in claim 6, in which the slab-like material from which the cradle is formed is corkboard.

8. A reservoir as defined in claim 6, in which the slab-like material from which the cradle is formed is balsa wood having its grain extending substantially perpendicular to the inner surface of the casing.

9. A reservoir as defined in claim 6, in which the slab-like material from which the cradle is formed is foam glass.
